TRAVELING CASE AND FIXTURE THEREFOR

Michael J. De Leonardis, Valley Stream, N. Y.

Application March 13, 1947, Serial No. 734,440

2 Claims. (Cl. 190—41)

1

This invention relates to hand luggage, such as wardrobe suitcases and the like, and to the fittings or fixtures therefor.

An object of the invention is to improve hand luggage and the fixtures therefor. Another object is to provide hand luggage with means in the form of fittings and fixtures for hanging clothing therein in a folded condition. A further object is to provide a fixture for luggage, such as a wardrobe suitcase, which efficiently and compactly folds and stores garments in part of the case, such as the cover.

Another object is to provide a fixture which is removable. A further object is to provide a fixture which can be economically manufactured principally of sheet or strip stock.

Other objects of the invention will be apparent from the following description and accompanying drawings taken in connection with the appended claims.

The invention accordingly consists in the features of construction, combination of elements, and arrangement of parts as will be exemplified in the structures to be hereinafter described and the scope of the application of which will be indicated in the following claims.

In the accompanying drawings in which are shown by way of illustration several possible embodiments of my invention:

Figure 1 is a perspective view of a wardrobe suitcase fixture embodying features of the invention, in open position, together with a garment hanger for use therewith, the wardrobe case in which the fixture is mounted being indicated in dot and dash lines;

Figure 2 is a section on the line 2—2 of Figure 1, but showing the fixture in closed or folded position, the folded position of a garment on the fixture being indicated in dashed lines;

Figure 3 is a detail view of the self-locking hinge of the fixture;

Figure 4 is a detail view in perspective of the hanger support;

Figure 5 is a detail of the hanger;

Figure 6 is a detail of a modified fixture construction;

Figure 7 shows part of a detachable fixture construction;

Figure 8 is a detail of the fixture of Figure 7 in detached position;

Figure 9 is a sectional elevation of a further modified fixture, mounted in a wardrobe suitcase;

Figure 10 is a section of the suitcase on the line 10—10 of Figure 9 showing the fixture in top view;

2

Figure 11 is a detail of a modification of the fixture of Figures 9 and 10;

Figures 12 and 13 are details of other forms of the invention;

5 Figure 14 shows another detachable fixture;

Figures 15, 16 and 17 are details of the fixture shown in Figure 14;

Figures 18 and 19 are details of another form of detachable connection for a fixture; and

10 Figures 20, 21 and 22 are details of another detachable connection.

While a preferred embodiment of the invention is described herein, it is contemplated that considerable variation may be made in the method of procedure and the construction of parts without departing from the spirit of the invention. In the following description and in the claims, parts will be identified by specific names for convenience, but they are intended to be as generic 20 in their application to similar parts as the art will permit.

Referring to the drawings, and particularly to Figures 1 to 5, there is illustrated a fixture comprising a stationary frame section 30 mounted within the cover 31 of a wardrobe suitcase 32. A garment hanger support 33 for garment hangers, such as hanger 34, is secured to the frame section 30.

25 The folding parts of the fixture comprise a folding middle section 35 hingedly connected to stationary frame 30 and a folding end section 36 hingedly connected near the outer end of middle section 35.

The wardrobe suitcase 32 and its cover 31 are 30 hinged together along meeting edges 37 by hinges 38 in the customary manner and are provided with the usual latches or lock members 39 and 40 for locking the cover closed. The case may also have a carrying handle 41 attached in the usual manner.

35 The flexible flap or curtain member 42 may also be secured to the cover along the edge opposite to the hinged edge 37 so that it can hang in front of the cover space when the cover is in open position at right angles to the case 32 and the case is lying flat on a horizontal surface such as a table top or can be thrown back over the top edge of the open cover to expose the inside of the cover to view. The free lower edge of the flap 42 is preferably provided with means, such as snap fastener elements 43 to co-operate with snap fastener elements 44 mounted on the lower part of stationary frame section 30 to enclose the cover space when it has been packed, and form a partition 45 between the cover space and the main case space when the case is closed.

40

45

50

55

Stationary frame section 30 comprises a frame strip 45 bent into a right angle U shape to provide a mid-portion 46 which fits inside the upper edge wall of the cover and a pair of side arms 47 and 48 which fit inside the two side walls of the cover. Strip 45 is provided at spaced points with rivet holes 49 in which are riveted suitable rivets or eyelets which also pass through one or more layers of the material forming the walls of the cover 31 to firmly secure frame section 30 in place within the cover.

Garment hanger support 33, shown in detail in Figure 4, comprises a strip of flat metal stock bent into a generally rectangular shape. The strip is first punched to provide a longitudinal slot 50 having an enlarged end opening 51, which may be of semi-circular shape, for permitting insertion of the enlarged end 52 of the hanger arm 53 of a garment hanger 34 (Figure 5). When the support 33 is bent into elongated rectangular shape the narrow part of slot 50 is disposed along one of the longer sides and extends around the front corner where it merges in the short front end face with opening 51. The front end face of support 33, carrying opening 51, is bent back at a slight angle. It will thus be evident that one or more hangers 34 can be placed on the support by inserting the upper enlarged end 52 of each hanger through opening 51 and sliding it back until the shoulders 54 of the hanger arm rest on the two edge strips which define slot 50 between them. It will also be evident that the hangers cannot readily slide out accidentally since part of slot 50 extends around the corner of the support member so that its edge strips form shoulders over which the hanger shoulders 54 must be lifted to remove the hangers.

The ends of sheet metal strip forming support 33 are offset laterally in opposite directions so that when the strip is folded a pair of riveting lugs 55 and 56 are provided which extend out to the two sides of the top part of support member 33. The edges of the piece are curved in such a manner that the lugs fit into complementary spaces and their rivet holes 57 are aligned along a line transverse of the support. The support is also provided with a pair of rivet holes 58 by which it is riveted to the middle portion 46 of frame member 45 before the frame is secured in position in the cover 31 of the case. When the frame is installed the support 33 is riveted directly to the cover of the case by suitable rivets through holes 57.

The remainder of stationary frame section 30 comprises a pair of brackets 60 secured to the lower ends of side arms 47 and 48 of U-shaped frame strip 45, and a flat bottom bar 61 bridging the space between brackets 60 and completing the fourth side of the stationary frame section 30. Brackets 60, shown most clearly in Figure 3, are sheet metal stampings formed with a channel portion 62 into the lower ends of which frame arms 47 and 48 are secured by rivets 63 and a flat support portion 64 in which is secured a headed pivot pin 65, which may comprise a rivet for hingedly mounting the arms 66 of folding middle section 35 of the fixture. Side arms 66 are slotted to form a sliding and pivoted connection with pivot pins 65. A pair of ears 68 and 69 are bent up at right angles to the material of bracket 60 below the mounting area of pivot pin 65 to provide a channel 72 having a width slightly greater than the width of arms 66 so that, when the frame 35 is turned up it is closed in such a manner that side arms 66 will slide downward

by virtue of the pin-and-slot connection of pin 65 and arms 66 until the lower ends of arms 66 enter the channel formed by flanges 68 and 69 thereby locking the frame 35 in closed position.

Bottom bar 61 is riveted at its ends by rivets 70 to the outer faces of flanges 69. While this bar may extend straight across the intervening space it is preferred, as shown, to provide offset ends 71 on the bar so that the main body of bar 61 is spaced about two or three inches (2" or 3") above the lower edge of cover 31. As previously mentioned, snap elements 44 are riveted to bar 61 near the two ends of its middle portion and these elements co-operate with complementary snap-fastener elements riveted into the lower edge of curtain 42.

Folding middle section 35 of the fixture comprises a horizontal garment bar 73 formed of a strip of sheet metal having its outer edge bent into a tubular portion 74 providing a smooth rounded engaging surface over which garments can be folded without damaging or unduly creasing them. One edge of the sheet metal adjoining the part 74 which is bent into tubular shape comprises a flat portion 75 extending out from the edge of tubular part 74 and the outer edge of flange 75 is bent upward at an angle of 30 degrees or so to provide a shoulder 76 which will serve as a stop for folding end section 36 of the fixture. The ends of flat portion 75 of garment bar 73 project through slots in the pair of sheet metal strips 66 comprising the side arms of folded middle section 35 and are expanded, peened or spread out against the outer faces of bars 66 to anchor garment bar 73 to the side arms. Side arms 66 are provided with double bends 77 near their pivoted ends to narrow the width of frame 35 beyond the pivots whereby it will fit easily within the cover when it is folded upward.

Folding end section 36 of the fixture is generally similar in construction to middle section 35. It comprises a garment bar 78 having a substantially tubular garment engaging edge 79 and a flat flange 80 to increase its stiffness. The two side arms 81 of end frame section 36 are straight flat metal strips which are slotted near their outer ends and which are riveted at their inner ends by rivet 82 to the inside faces of bars 66 of middle frame 35 immediately to the rear of upturned flange 76 of garment bar 73. The rivets are either formed of a relatively soft metal such as soft aluminum or are not tightly riveted into place so that they permit the arms 81 to rotate on the rivets as a pivot pin. Flat portion 80 of garment bar 78 projects through the slotted ends of arms 81 and the ends of the projections are spread or peened over to secure the parts together.

Figure 1 shows the fixture in the position it would occupy if it were mounted in the cover 31 of wardrobe suitcase 32 and the suitcase were resting on a table with the cover opened to vertical position and with sections 35 and 36 of the fixture folded out to open position. The relationship of the pivot pins 65 upon which middle frame section 35 is pivoted and the upper edges of flanges 69, which are located below the pivot areas on brackets 60, is such that the upper edges of flanges 69 provide stops or rests for side arms 66 so that they are held in substantially horizontal position when section 35 is folded outward. The relationship of rivets 82 and angular flange 76 of garment bar 73 is such that when folded end section 36 of the frame is folded out it will be brought to a stop when side arms 81

come against the edge of flange 76. This takes place when arms 81 are slightly beyond vertical position. It will be seen therefore that the frame can rest naturally in the open position shown in Figure 1 without outside support.

When it is desired to pack the case for traveling, garment hangers, such as hanger 34, having garments supported thereon in the usual manner are inserted in hanger support 33 by placing their enlarged ends 52 through opening 51 and sliding them back in slot 50. The garments hanging from hanger 34 are draped over garment bar 73 of middle frame section 35. When all the garments have thus been draped, the cover folding section 36 of the fixture is folded down over the garments so that garment bar 78 engages the middle portion of the garments at about the point required for the first fold, that is near the lower edge of cover 31. Folding middle section 35 is folded back into the cover and is then allowed to fall sufficiently so that slots 67 slide on pivot pins 65 and the lower ends of arms 66 become engaged in channels 72 thereby locking the frame closed. While this is being done it is usually convenient to throw curtain or flap 42 back over the outside upper edge of cover 31. When the frame has been folded into closed position flap 42 can be brought down and secured over the front of the cover by snap fasteners 43 and 44. The closed position of the fixture is shown in Figure 2. It will be noted that garment bar 78 of folding end section 36 is now disposed behind stationary bottom bar 61 of the frame inside the cover and that garment bar 73 of folded middle section 35 is disposed inside the cover near the top edge. The garments, indicated by dashed line 83, which depend from hanger 34, pass down underneath garment bar 78 then upward over garment bar 73 and the free lower ends of the garments hang down in front of bar 73 protected by curtain 42 when it is snapped over the face of the cover.

While almost any metal may be used for the parts of the fixture I prefer to use a light metal such as aluminum to reduce the overall weight of the suitcase. The pivot rivets can be formed of cold soft aluminum so that they will loosen up sufficiently after riveting to permit pivotal motion of the parts.

The preferred garment hanger 34 for use with the suitcase is shown in Figure 1 and details of the manner of assembly in Figure 5. The hanger comprises an aluminum wire 84 bent into generally triangular shape with a broad base and rounded lower corners and having the ends of the wire meeting in axially aligned relation at the crest. A substantially circular piece of sheet aluminum 85 is folded across its middle around the wire to cover the joint. One side 86 of the folded piece 85 is bent around the aligned ends of wire 84 to provide a substantially tubular sleeve portion while the other half 87 of the sheet metal piece remains substantially flat. After assembly of part 85 over the ends of wire 84 it is stamped with a bluntly pointed tool at two or more points along its crest to form dents or depressions 91 in the wire and force the sheet metal into it, thereby locking the wire ends in the folded piece.

Hook member 53 of the hanger comprises a piece punched from a flat sheet of aluminum as a straight rod. It is then bent into the hooked shape shown to form a hook portion 88 of suitable dimensions for hooking over a closet rod or the like when the hanger is removed from the

wardrobe suitcase. The end of the hooked portion 88 is provided on its inside edge with a rounded projection 89 which aids in preventing the hook from accidentally slipping off a closet rod, particularly small rods of polished metal and the like. A rivet hole is provided in member 53 above hook portion 88 and it is secured by rivet 90 which passes through hook member 53 and the two halves 87 and 86 of folded piece 85. The rivet, being formed of soft aluminum, loosens up sufficiently after riveting to permit hook member 53 to swivel on the wire frame. The end of member 53 opposite to hook 88 is cut, as previously described in part, to provide a shank portion 92 terminating in an enlarged head 52 providing shoulders 54 at the two edges of the shank for supporting the garment hanger in slot 50 of support 33. It will be apparent that hook member 53 can be swiveled on rivet 90 to bring either hook 88 or head 52 uppermost depending upon whether it is desired to use the hanger in a closet or in the traveling case.

Figure 6 illustrates a modification in which a large part of the stationary frame inside the cover is eliminated. In this embodiment the arms 66 of the folding middle section of the fixture are pivoted on pivot pins 94 secured to sheet metal brackets 93, each of which comprises a flat body portion carrying the pin 94 and having an arm extending rearwardly into the cover of the suitcase and provided with holes 95 in which are mounted rivets or screws for fastening the bracket to the sides of the cover. A pair of flanges 96 and 97 are turned up at right angles to the body of the bracket to form a channel 98 between them for receiving the end of arm 66 to lock the folding frame closed, in a manner similar to that described in connection with Figures 1 to 3. While a stationary bottom bar (such as 61, Figure 1) can be secured between flanges 97 of a pair of brackets 93, it can be eliminated for economy and weight-saving and snap-fastener elements 44 riveted directly to flanges 97. This produces an extremely simple and lightweight fixture having all the advantages and the same mode of functioning as the fixture of Figures 1 to 3.

Figures 7 and 8 show a fixture of different construction for performing the same functions as those previously described. Moreover, this fixture is provided with a detachable folding section which can be removed when not required. The fixture comprises a pair of brackets 100, one of which is shown in Figure 7. It comprises a strip of sheet metal curved back at the top end to provide a portion 101 substantially at right angles to the main body of the strip, but in the same plane therewith. The end of portion 101 is bent at right angles to this plane and again bent at right angles to provide a flange 102 in spaced parallel relation to the body of portion 101. A latch member 103 is pivoted between portion 101 and flange 102 on a pin or rivet 104 extending through aligned openings in each. Member 103 comprises a flat sheet metal piece cut or punched to provide a pivot hole at one end and having a tapered free end providing an inclined camming surface 105 having a notch 106 therein for receiving a pin 107 on the folding frame part. A wire spring 108 is wound around pivot pin 104 and has one end hooked over latch member 103 and the other end over the top of the bent end of portion 101 to apply a spring pressure to latch 103 tending to turn it downward. The rear end of latch 103 is formed with a substantially square corner 109 at its lower edge. This abuts against

the inside of the channel formed by flange 102 to stop latch 103 in a rest position which is substantially horizontal.

Folding frame section 110 comprises a garment bar 111, similar in construction to bar 78 of Figures 1 and 3, and a pair of side arms 112, one of which is shown in Figures 7 and 8, which are pivoted on pivot pins, such as pin 113 staked into brackets 100. The spacing between pivot 113 and latch pin 107, which is staked into the outside face of side arm 112, is equal to the spacing between pin 113 and the bottom of notch 105 in latch 103 so that, when frame 110 is pivotally turned upward to closed position, pin 107 will engage cam surface 105 and raise latch 103 sufficiently to allow pin 107 to enter notch 106. Spring 103 will then snap the latch down over the pin to securely latch the folding frame section in closed position. The section can be opened out at will by manually lifting latches 103 to permit frame 110 to fold outward.

The mode of detachably attaching side arm 112 to pivot pin 113 is shown most clearly in Figure 8. Pin 113 is a straight pin having a pair of annular grooves 114 therein spaced apart by a distance slightly greater than the thickness of arm 112. Arm 112 has a pivot hole 115 therein and two pairs of opposed notches 116 in its edges on opposite sides of the pivot hole. A wire clip 117 is fitted over arm 112. While variations in form of the wire clip are possible the preferred one illustrated comprises a single piece of wire bent to provide four rectangular loops 118 which rest in notches 116 and three bowed spring arches 119 which snap into grooves 114 of the pivot pin when the arm is inserted over the pin. If it is desired to remove the folding section 110 it is merely necessary to press arms 112 together with sufficient force to dislodge spring arches 119 from grooves 114 and bend arms 112 inward to clear the free ends of pins 113.

A stationary bottom bar 129 comprising a metal strip having right angle flanges at its ends is riveted to the outer faces of brackets 100 below the pivot pin. When folding frame section 110 is folded outward the upper edge of bar 129 provides a stop for the frame when it is in substantially horizontal position.

A right angle flange 121 is bent up from the rear edge of bracket 100, or may be provided as separate piece riveted thereto. This flange carries a pivot pin or rivet 122 on which is pivoted a sheet metal arm 123 made of two flat strips 124 and 125 which slidably overlap to form a telescoping mid-section. The overlapping ends of the strips are provided with pairs of integral fingers 126 on opposite edges. Fingers 126 of each strip are bent around the body of the companion strip to slidably hold the two strips together in telescoping relation.

The end of inner strip 124, which is pivoted on bracket 121 has a loose slot connection 127 with rivet 122 so that, when the arm 123 is first tilted backwardly so as to clear latch bracket 102 and then folded up to vertical position along one edge of the cover of the wardrobe suitcase the lower end may be slid downward. This locks the arm 123 in folded-up position out of the way along the edge of the cover by virtue of the abutment of the side of strip 124, at its lower end, against the face of bracket 100. The free end of strip 125 is provided with a hole 128 of keyhole shape which fits detachably over a pin or rivet mounted on a flange similar to flange 121 on the comple-

mentary bracket 100 in the other side of the cover of the case.

In this embodiment the arm 123 performs the function of garment bar 78 of Figure 1. Arm 123 is kept folded up out of the way while garments are being hung in the cover and is then folded down against the mid-portion of the garments and hole 128 fitted over the head of the pin or rivet on the opposite bracket. Then folding frame section 110 is folded up until it is latched closed by latch 103.

Figures 9 and 10 illustrate a modified fixture mounted in the cover 31 of wardrobe suitcase 32. This comprises a pair of sheet metal brackets 129 in the form of flat metal strips screwed or riveted to the side walls of the cover, as by screws 130. Right angle flanges 131 are bent up from the inner and outer edges of each strip near its lower end. Side arms 132 of folding middle section 135 of the frame are slotted at their inner ends and pivoted on rivets 133 in brackets 129. When the frame is folded out the side arms rest on outer flanges 131 so that frame 135 is suspended in a substantially horizontal position, as shown in Figures 9 and 10. A garment bar 134 is secured between the outer ends of arms 132. A pair of inturned right angle flanges 137 are provided on arms 132 near their inner ends and carry snap fastener elements 44 into which elements 43 on curtain 42 are snapped when the curtain is fastened down in position. Side arms 132 have double bends 138 near their pivoted ends to narrow the width of the folding middle section and allow good clearance at the sides between the frame and the walls of the cover.

Folding end section 136 of the fixture of Figures 9 and 10 comprises a garment bar 139, which is shorter than bar 134, and which is secured to a pair of side arms 140 which are provided with double bends 141 so that their inner, or pivoted, ends lie slightly outside arms 132 of frame section 135 where they are pivoted to arms 132 by rivets 142. A washer 143 is interposed between each of arms 140 and arms 132 to space the outer arms 140 above the projections on the outside of arms 132 caused by staking the ends of bar 139 into them. When the fixture is opened up, as shown in Figures 9 and 10, arms 140 rest on the edge of case 32. They are formed with angular bends 143 at this point so that the free end of end section 136 projects outward and upward at a slight angle. When the fixture is folded up end frame section 136 is turned upward and inward until the parts of arms 140 between double bends 141 rest on arms 132 of middle frame section 135 and garment bar 139 is positioned above and adjacent to arms 132 near their pivoted ends. The middle section is then folded into the cover where it is held by the flanges 131 due to the slots in arms 132 sliding down on rivets 133 to locking position.

Figure 11 shows a modification of the fixture of Figures 9 and 10. In this embodiment a folding end section 146 is provided in place of section 136. Garment bar 145 is longer than bar 134 of the middle section and side arms 144 are not provided with double bends 141 which were present in bars 140. Hence when end section 146 is folded inward arms 144 lie outside arms 132 and cross them only near their inner ends between double bends 138. In this embodiment a curtain fastener bar 147 is indicated as extending across the space between arms 132.

Figure 12 illustrates a modification of the fixture of Figures 7 and 8 in which curtain fastener

bar 120' and folding garment hold-down arm 123' are mounted on side arms 112' of folding frame 110 instead of on stationary fixture 100. Here the rivet 148 on flange 149 on one of the arms 112 provides an anchor pin over which hole 128' on the end of arm 123' is fitted when arm 123' is in use. Arm 123' swings outward on its pivot rivet 122 on opposite flange 149 but here it is not necessary for it to have a slotted connection with the rivet.

Figure 13 shows a modification of the fixture of Figure 7. In this embodiment the side arm 153 of the folding section is permanently attached to bracket 190 by a rivet 151. Also, instead of a stationary curtain hold down bar 120, a bar 152 is provided which has a double bend to bring the inner portion of the bar up two or three inches from the rear edge of the cover of the case.

Figures 14 to 17 illustrate a form of detachable fixture which is generally similar to that of Figure 12 but which has a different modification of detachable clip and a different shoulder arrangement. Brackets 153, comprising sheet metal plates are arranged to be screwed or riveted to the opposite inside walls of the cover of a travel case by means of holes 154. Each has a right angle flange 155 bent up from the rear edge at an intermediate point. Below flange 155 the flat body of each plate is extended rearwardly in a triangular area 156 beyond the line of the vertical rear edge of the plate and the sheet metal bent at right angles to the vertical rear edge of the triangular area 156 to provide a beveled flange having a sloping portion 157 and a vertical portion 158 joined to the lower edge of the sloping portion. A clip member 159 formed of thin sheet metal, such as sheet steel, is permanently riveted, by rivet 160 to the face of each bracket plate 153. Clip part 159 comprises a channel having a dished bottom 161 in which the head of rivet 160 is disposed, a pair of side flanges 162 spaced just wide enough to receive the width of end portion 163 of arms 164 of detachable folding frame section 165, and a pair of bent in ears 166 (Figures 15 and 16) at the outer end of the clip part. Arms 164 of the folding frame each comprise a strip of sheet metal of a width corresponding to the spacing between flanges 162. Each arm has a pair of rectangular notches cut into its two sides near its pivoted end to provide a narrow shank portion 167 between the main body of arm 164 and end portion 163, which may be of the same width as the body. Thus, arm 164 may be laid against clip part 159 with end portion 163 held in the channel formed by the clip and the shoulders formed where end portion 163 adjoins shank 167 abutted against ears 166 of the clip part. In order to secure arm 164 to the clip a second clip part 168 is provided which comprises a channel formed of thin sheet metal, such as steel. Channel 168 has a central body 169 which overlies the top face of arm portion 163, a pair of side flanges 170 which lie outside flanges 162 of clip part 159 and a pair of inturned flanges 171 on the edges of flanges 170 which extend under clip part 159 along the border of dished bottom 161 thereby to secure part 168 to part 159. An upturned ear 172 is provided on the outer end of body 169 to permit manual sliding of the clip part 168 along the part 159 and arm 164 to disengage the two clip parts 159 and 168 and thereby permit detachment of arms 164 from the pivot. Channel 168 has a pair of inturned ears 173 on side flanges 170 at the outer end which serve as stops to prevent clip

part 168 from sliding off the rear end of part 159. With arm 164 pivoted on bracket 153 by being held in assembled clip parts 159 and 168 the folding frame section 165 can be folded in and out of the cover. The relationship of pivot rivets 160 and flanges 155 on brackets 153 is such that the upper edges of end portions 163 of the arms come against the lower edges of flanges 155 as a stop when frame 165 is opened out to a substantially horizontal position. The end of portion 163 is preferably curved to slide readily on the inside face of flange 157 when the frame is folded up. When the frame reaches vertical, or closed, position the portions 163 can slide downward in the tubular housing formed by clip parts 159 and 168 until it occupies the position indicated in dotted lines in Figure 16. In this position the normally upper edge of portion 163 abuts against lower flange portion 158 of bracket 153 thereby locking the frame in closed position. When it is desired to open the frame it is first lifted to draw portion 163 partly into the pivot clip member, thus bringing the curved end of portion 163 into clearance with flange portions 157 and 158.

The remainder of frame 165 is generally similar to frame 110 of Figure 12.

Figures 18 and 19 show another detachable clip 174 for co-operation with an arm 175 to form a detachable connection to pivot pin 176 on stationary bracket 177 having a stop flange 178. Arm 175 is a strip of sheet metal having a pivot hole 179 near its inner end which fits loosely over pin 176. Pin 176, which is staked into bracket 177 has a straight body having an annular groove 180 near its outer end. Clip 174 is formed with a flat outer face 181 provided with flanges 182 at its edges and inturned flanges 183 on the edges of flanges 182 to provide a channel which can be slid over the end of arm 175. Face 181 is slotted inward from the rear end with a slot 184 which is narrower than the diameter of pin 176 but wide enough to slip into groove 180 thereby to lock clip 174 and arm 175 to the pivot pin. An upturned ear 185 is provided on the outer end of face 181 for manual sliding of the clip into and out of locking position. Flange 178 is in a location to stop the rotation of arm 175 when it reaches substantially horizontal position.

Figures 20, 21 and 22 show still another form of detachable pivot coupling for the folding frame. This comprises a stationary bracket 186 formed of sheet metal the body of which has part of its material formed into a cup-like shell 187, by drawing for example. Shell portion 187 stands up from the plane portion of bracket 186 as an annular boss having a plane top wall 188 and a practically cylindrical side wall 189. Part of the side wall 189 is cut away to provide a slot 190 extending for slightly more than 90 degrees around the shell portion on the outer side of the bracket as mounted inside the cover of a travelling case. A radial slot 191 is cut in top wall 188 from the mid-portion of the edge bordering slot 190 and extending to the middle of wall 188. A latch member 192 comprising a circular disc of heavy sheet metal having a radially projecting lever 193 on its outer edge is received in shell portion 187 with lever 193 projecting out through slot 190. A radial slot 194 is cut in disc 192 corresponding to slot 191 in wall 188. When lever 193 is in uppermost position in slot 190 slots 191 and 194 are aligned and together form a single slot for the reception of the shank of a rivet 195 staked in the end of arm 196 of a folding frame

section. Thus by raising lever 193 the arm may be attached to the bracket by inserting head of rivet 195 underneath disc 192 and sliding the shank of the rivet back in the aligned slots until it reaches the middle of wall 183. Latch lever 193 is then turned or allowed to fall to lowermost position thereby turning slot 194 substantially at right angles to slot 191 and locking the arm to the bracket in pivotal fashion. The arm can readily be removed by lifting latches 193.

It will be evident that certain features of one fixture may be combined with certain features of other fixtures to form a variety of combinations in addition to those illustrated.

While the present invention, as to its objects and advantages, has been described herein as carried out in specific embodiments thereof, it is not desired to be limited thereby but it is intended to cover the invention broadly within the spirit and scope of the appended claims.

What is claimed is:

1. A fixture for supporting and folding garments in a wardrobe suitcase comprising, in combination, a pair of bracket members having means for attaching said members to the inside face of opposite side walls of a cover of a wardrobe suitcase and having thereon pivot means and locking means, a folding frame section comprising a garment support bar and a pair of side arms each secured adjacent one of its ends to an end of said garment support bar and each pivoted adjacent the other of its ends on said pivot means on the respective bracket member, separate shoulder means on each of said bracket members to limit the pivotal motion of said arms in an outward direction with respect to said cover to a position substantially perpendicular to said cover, cooperating locking means on each of said bracket members and each of said arms comprising a channel portion on each of said bracket members and an elongated slot in the end of each of said side arms receiving said respective pivot means, whereby said side arms and said frame section is reciprocable between a position in which the pivoted end of each of said side arms is within one of said channel sections and said side arm is locked in a closed position so that said garment support bar is positioned near one transverse wall of the cover, and a second position in which said pivoted ends of each of said arms is disengaged from said channel sections and said frame is free to fold out of said cover on said pivot means; a garment hold-down bar, and means pivotally supporting said bar for movement between a garment engaging position, in which said bar is positioned within said cover adjacent a transverse wall of said cover opposite to said transverse wall near said garment support bar, and a retracted position, in which said cover may be loaded with garments and said garments may then be engaged by and folded under said garment hold-down bar and then over said garment support bar.

2. A traveling case comprising, in combination, a body and cover hinged thereto along one edge thereof, the inside of said cover providing a re-

cess for the storage of garments, a garment hanger support mounted adjacent to an inside wall of said cover opposite said hinged edge, a pair of bracket members each mounted on an inside wall of said cover adjacent to the said hinged edge, pivot pins and locking means on said brackets, a folding frame section comprising a garment support bar and a pair of side arms each secured adjacent one of its ends to an end of said garment support bar and each pivoted adjacent the other of its ends on the pivot pin on one of said bracket members by means of an elongated longitudinal slot therein slideably fitting over one of said pivot pins, said locking means comprising a channel formed in each of said brackets arranged to receive the pivoted end of the respective side arm when said pivot pin is at one extremity of said elongated slot, whereby said folding frame section can be folded into said cover to bring said garment support bar within said cover to a position adjacent said inside wall opposite said hinged edge, separate shoulder means on said bracket to limit the pivotal motion of said arms with respect to said cover; a garment hold-down bar, and means pivotally supporting said bar for movement into a garment engaging position, in which said bar is within said cover adjacent to said hinged edge and parallel thereto, whereby said cover may be loaded with garments by suspending from said garment hanger support said garments while said garment support bar is in a position folded out of said cover and said garment hold-down bar is folded out of said garment engaging position, and whereby said garment hold-down bar can then be folded down over a mid-portion of said garments and said folding frame section can be folded into said cover to thereby fold said garments over said garment support bar.

MICHAEL J. DE LEONARDIS.
